Primary Examiner — Wendy L Arminio*Assistant Examiner* — Tracey J Bell(74) *Attorney, Agent, or Firm* — Taft Stettinius & Hollister LLP(57) **CLAIM**

The ornamental design for a bracelet, as shown and described.

DESCRIPTION

FIG. 1 is a front elevational view of a bracelet showing my new design;

FIG. 2 is a back elevational view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is a front, bottom, right side perspective view thereof; and,

FIG. 8 is a back, bottom, left side perspective view thereof. The broken lines depict portions of the bracelet that form no part of the claimed design.

1 Claim, 8 Drawing Sheets(56)
